LOOSE LEAF BINDER

George H. Dawson, Chicago, Ill., assignor to
 Wilson-Jones Company, Chicago, Ill., a corpo-
 ration of Massachusetts

Application May 17, 1935, Serial No. 21,923

6 Claims. (Cl. 129-8)

This invention relates to loose leaf binders of the type having a locking post between the covers, as disclosed in U. S. Letters Patent No. 927,741 granted to W. S. Mendenhall July 13, 1909, and 5 more particularly to the locking post and the means for operating the same.

It is an object of this invention to provide simple and efficient means for rotating one section of the locking post a predetermined distance 10 to lock and unlock the post sections. Other objects of this invention will become apparent upon reading the following description taken in conjunction with the accompanying drawing in which

15 Figure 1 is a fragmentary perspective view of a loose leaf binder embodying my invention;

Figure 2 is a front elevation of the binder shown in Figure 1, with parts broken away to facilitate illustration of the post structure;

20 Figure 3 is a cross sectional view of the binder showing the locking post in locked position;

Figure 4 is a fragmentary top plan view of the binder with parts broken away; and

25 Figure 5 is a fragmentary perspective of the two sections of the binder in disassociated relationship.

In the drawing, the reference numerals 2 and 3 indicate a pair of telescoping back sections. Cover members 4 and 5 are secured to the back sections in any suitable manner. The back section 2 has a plurality of sheet retaining posts 6 secured thereto in any conventional manner. The section 3 is provided with a flat bar 7 to which sheet retaining posts 8 are secured. Although the posts 6 and 8 may be of any desired type, I prefer to provide telescoping posts as illustrated in Figure 2.

The means for locking the binder sections comprises a tubular post 9 secured to one back section 2, and a locking post 10 secured to the other back section 3. The tubular post 9 is provided on its inner surface with opposed series of serrations or mutilated threads 11. The locking post 10 is provided with opposed series of serrations or threads 12 adapted to mesh with the serrations or threads of the tubular post.

The locking post 10 is provided with reduced neck portion 13 which extends through an aperture in the flat bar 7. A washer 14 is positioned over the neck above the bar 7, and the end of the neck 13 is spun down against the washer 14, as indicated at 15, to swivel the locking post 9 to the bar 7. A lever 16 is fixed to the locking post 10 so that rotation of the lever will rotate the locking post. The lever 16 is provided with an up-

standing lip or flange 17 adapted to facilitate the manipulation of the lever. The flat bar 7 is cut away, as indicated at 18, to provide convenient access to the flange 17 when the lever is in locking position.

The rotation of the lever 16 in each direction is limited by means of a stop member 19 (Figure 4). The preferred form of stop member consists of a single projection depending from the underside of the flat bar 7. As shown in Figure 4, the lever 16 is provided with two extensions or shoulders 20, 21 adapted to abut the stop member 19 when the lever 16 has been rotated a predetermined distance in either direction. The stop member 19 may be struck from the bar 7, or may be formed separately and welded thereto.

The operation of the locking post is very simple. After the sheets 22 have been impaled on the tubular post 9 and on the sheet retaining posts 6, the back section 3 is positioned with the posts 8 telescoping the posts 6 and the locking post 10 inside the post 9, and then the lever 16 is moved to the position of Figure 5. The locking post is shaped like a flattened circle in cross section, and when the lever is in the position of Figure 5 the major axis of this flattened circle lies between the serrations or threads 11 on the inside of the tubular post 9. The two binder sections are then engaged and are compressed to hold the sheets tightly. While the contents are compressed by the back sections the lever 16 is rotated to the locking position indicated in Figure 1. In this position the threads or serrations 12 are engaged with the threads or serrations 11 so that the binder sections cannot be separated without first moving the lever 16 to the unlocked position illustrated in Figure 5.

The binder may be provided with a transfer bar 23 having positioning pins 24 projecting from its upper surface and sheet aligning pins 25 projecting from its lower surface. When the binder is to be used with a transfer bar, the bar 7 is apertured, as indicated at 26, Figure 2, to receive the positioning pins 24.

Although I have described a preferred embodiment of my invention in detail, it will be understood that the description thereof is illustrative, rather than restrictive, as many details may be modified or changed without departing from the spirit or scope of my invention. Accordingly, I do not desire to be restricted to the exact construction described, except as limited by the appended claims.

I claim:

1. In a loose leaf binder, a cover member, a

- bar secured to said cover member, a locking post rotatably secured to said bar, a lever secured to said post for rotating the same, and means projecting from said bar and engaging said lever to limit the rotation of said post.
5. In a loose leaf binder, a cover member, a bar secured to said cover member, a locking post swiveled on said bar, a lever rigidly secured to said post, a lip on said lever to facilitate rotation of said post, an extension on said lever, and a projection on said bar engaging said extension to limit the rotation of said post.
10. In a loose leaf binder, a cover member, a bar secured to said cover member, a locking post swiveled on said bar, a lever fixed to said post, a stop member projecting from said bar, and a pair of spaced shoulders on said lever adapted to engage said stop member to limit the rotation of said post in either direction.
15. In a loose leaf binder, a cover member, a bar secured to said cover member, a locking post swiveled on said bar, a lever rigidly fixed to said locking post, said lever adapted to be swung in a plane parallel to and adjacent the plane of said bar to rotate said locking post, a lip on said lever
20. 4. In a loose leaf binder, a cover member, a bar secured to said cover member, a locking post swiveled on said bar, a lever rigidly fixed to said locking post, said lever adapted to be swung in a plane parallel to and adjacent the plane of said bar to rotate said locking post, a lip on said lever
25. 5. In a loose leaf binder, a cover member, a bar secured to said cover member, a locking post swiveled on said bar, said locking post being non-circular in cross section and having transverse serrations along two diametrically opposed edges, means secured to said locking post, and means on said bar adapted to cooperate with said first mentioned means to prevent the rotation of said locking post in either direction beyond predetermined limits.

to facilitate manipulation thereof, and means to prevent said lip from contacting said bar.

5. In a loose leaf binder, a cover member, a bar secured to said cover member, a locking post swiveled on said bar, said locking post being non-circular in cross section and having transverse serrations along two diametrically opposed edges, means secured to said locking post, and means on said bar adapted to cooperate with said first mentioned means to prevent the rotation of said locking post in either direction beyond predetermined limits.

10. 6. In a loose leaf binder, a cover member, a bar secured to said cover member, a locking post rotatably secured to said bar, said locking post being shaped to approximate a flattened circle in cross section and having transverse serrations along the edges at opposite ends of the major axis of the flattened circle, a lever rigidly fixed to said locking post, means on said lever to facilitate rotation of said post, and means projecting from said bar to cooperate with said lever to limit the rotation of said locking post in either direction.

20. GEORGE H. DAWSON. 25
